UNITED STATES PATENT OFFICE

MENAHEM RIVKIN, OF PHILADELPHIA, PENNSYLVANIA

THROTTLE VALVE

Application filed September 25, 1929. Serial No. 395,097.

My invention relates to certain improvements in throttle valves adapted to throttle the steam as it passes from a locomotive boiler, either to the superheater or to the cylinders of the locomotive.

One object of my invention is to so construct a throttle valve as to dispense with the usual double-seated single valve by providing a multiple-section valve in which the sections can be seated in sequence.

Another object of my invention is to so construct the valve that its construction will be simplified, the valve occupying a small space within the dome or other portion of the locomotive.

A still further object of the invention is to provide a multiple valve in which the pilot valve is formed on the stem and the other sections are balanced prior to being actuated by a continued movement of the stem.

In the accompanying drawings:

Fig. 1 is an enlarged sectional elevation of my improved throttle valve;

Fig. 2 is a sectional elevation showing the valve located in a casing designed to occupy space in the steam dome of a locomotive;

Fig. 3 is a detached sectional view of the main section of the throttle valve;

Fig. 4 is a section on the line 4—4, Fig. 3;

Fig. 5 is a detached sectional view of the inner section of the valve;

Fig. 6 is a view showing the valve located in the superheater header of a locomotive; and

Fig. 7 illustrates a modification of the invention.

Referring to Figs. 1, 2 and 3, 1 is the valve casing, in the present instance adapted to be located in the dome of a locomotive boiler.

40 The casing has an extension 2 at the lower end adapted to be coupled to the dry pipes of the boiler, and forming an integral part of the casing, in the present instance, is an internal ring 3, and directly above the ring are outlets 4 for any intrapped water of condensation that may accumulate above the valve.

In the present instance, I locate within the ring 3 a seating ring 5 having a beveled seat 6, upon which the beveled portion 7 of the main valve section 8 rests when in a closed

position. The main valve 8 has guiding fingers 9 which extend through the ring 5, and act as guides for the valve when in the open position. 10 is a stem which extends through the valve and has its lower bearing in a bushing 11 which is located in a bearing 12 connected to the main valve casing by arms 13. The main valve stem is preferably reduced at the point where it extends through the bearing.

55 The rod has a threaded portion 14 on which is screwed a pilot valve 15, and when this valve is in its proper position it is secured firmly to the rod by a pin 16. The rod has a collar 17 below the main valve, which is so located as to lift the main valve off its seat when the rod is raised a sufficient distance. The pilot valve 15 rests in its closed position against a seat 18 on the inner section 19 of the throttle valve. This inner section is beveled 60 at 20 and rests against a beveled seat 21 of the main outer section 8 of the throttle valve, as clearly shown in Fig. 1.

65 A space 22 is formed between the inner section of the valve 19 and the valve stem 10, and within the lower portion are internal ribs 23 which fit the portion 24 of the stem, and these ribs extend a trifle below the bottom of the valve 19 so as to allow the shoulder 25 of the portion 26 of the valve stem to come 70 in contact with the ribs to raise the valve 19 off its seat.

75 It will be noticed that an annular flange 27 is formed on the lower portion of the valve 19 which is located within a recess in a hub 28 formed integral with the main valve 8. The hub 28 does not fit snugly. The hub has 80 an opening 29 for the portion 26 of the stem. This opening is slightly larger than the stem, so as to allow any steam or water of condensation to flow from the interior of the inner valve section 19 when the valve is in the closed position, but is closed by the shoulder 25a on the enlarged portion 10a of the stem 10 when the stem is raised to lift the pilot valve 15 off its seat. By this construction 85 the steam which flows into the inner section 19 of the valve will flow into the space 22a between the hub and the lower end of the inner section 19 of the valve and substan- 90 95 100

tially balance the said inner valve so that it can be readily raised off its seat on the continued movement of the stem. When the valve is closed, the shoulder 25a moves away from the hub 28, and any water of condensation or intrapped steam can flow through the channels 30 between the hub 28 and the hub 31 which is formed integral with the main valve and through the passages 32 to the space below the valve. When drifting, the pilot valve can be partially opened to allow a small quantity of steam to pass through the inner section of the throttle valve to the dry pipe or other connection, as the shoulder 25a will only partially close the opening 29.

The stem 10 is connected at its upper end to a head 33, which is attached to a cross bar 34 by a pin 35. This cross bar is connected to arms 36 on a shaft 37 by connecting bars 38 guided by lugs on the outer casing.

The shaft 37 is turned in its bearings 38a by an operating lever at the cab of the locomotive which is connected by a rod to the arm 39 which is keyed to the shaft. In the present instance an arm 40 forming an integral part of the arm 39 acts as a stop to limit the movement of the shaft 37, the arm 40 coming in contact with an abutment 41 on the valve casing.

In Fig. 6 I have illustrated my improved throttle valve located in the header 42 of a superheater. Passage 43 of this header connects with the dry pipe valve of the locomotive. In the bottom of the superheater casing are openings for the superheater tubes. The valve stem 10c in this instance is adapted to fit in a bushing 11a in the lower bearing 12a and extends through a bushing 44 in the cap 45 of the superheater header.

The valve rod 10c is connected to an arm 46 on a shaft 37a, and attached to the shaft is an arm 39a connected to the operating rod leading to the cab of the locomotive. The superheater casing, in the present instance, is made in two parts, the main part 42 described above, and a part 47, both parts being flanged and secured together by bolts or other fastenings. The part 47 is recessed at 48 to allow the arm 46 when disconnected from the rod 10a to drop into the recess so that when the cap plate 45 is removed the rod with the valve attached can be readily removed from the casing.

The shaft 37a passes through a stuffing box in the part 47 as set forth and claimed in the companion application, filed September 25, 1929, Serial No. 395,098.

While I have described one arrangement by which the throttle valve can be located within a casing of a superheater, it will be understood that the arrangements can be modified without departing from the essential features of the invention.

In Fig. 7 I have illustrated a modification in which the throttle valve is made in two sec-

tions, the main section 8a and the pilot valve 15a, the pilot valve in this instance resting on a seat upon the main valve, the main valve resting on a seat ring of the casing. When the rod 10b is raised the pilot valve will be lifted off its seat, after which the collar 17a will engage the hub of the main valve and lift it off its seat. It will be understood, while I have shown the multiple valve made in two and three sections, the valve may be made in more sections than three without departing from the essential feature of the invention.

I claim:

1. The combination in a throttle valve, of a casing; a seat in said casing; a multiple throttle valve, the outer section of the valve arranged to rest upon said seat, said outer section having two hubs, one located above the other, the said outer section having radial spaces between the two hubs, the outer section having a valve seat and an inner section adapted to close against said seat; a rod extending through the said throttle valve; a pilot valve on the said rod adapted to close against a seat on the inner section, the inner section having internal ribs bearing upon the valve stem, the valve stem being enlarged below said inner section to form a shoulder which when the valve stem is raised will come in contact with the ribs and lift the inner valve off its seat after the pilot valve has been raised on the movement of the stem; and a collar on the stem arranged to lift the main valve after the inner valve has been raised.

2. The combination in a throttle valve of a casing; a seat in said casing; a multiple valve, the outer section of said valve arranged to rest upon the said seat, the said outer section having two hubs spaced apart to form channels, said outer section also having a valve seat, the inner section of the valve adapted to close against said seat; a stem extending through the valve and having a collar arranged to raise the main section of the valve off its seat, the upper hub of the outer section being spaced from the inner section; the opening in the upper hub being of greater diameter than the stem; a shoulder on the stem arranged to close the opening when the valve rod is initially raised; and a pilot valve on the rod arranged to close against a seat on the inner section of the valve, the inner section having internal ribs forming steam spaces between the valve and the stem.

MENAHEM RIVKIN.
